(57) **CLAIM**

The ornamental design for an sleeve for tar guide cotton of electronic cigarette, as shown and described.

DESCRIPTION

FIG. 1 is a front view of a sleeve for a tar guide cotton of an electronic cigarette showing my design;

FIG. 2 is a rear view thereof;

FIG. 3 is a left view thereof;

FIG. 4 is a right view of thereof;

FIG. 5 is a top view thereof;

FIG. 6 is a bottom view thereof; and,

FIG. 7 is a perspective view thereof.

The broken lines in the drawings depict parts of the sleeve for tar guide cotton of the electronic cigarette that form no part of the claimed design.
